(57) **CLAIM**

The ornamental design for a container for storing and shipping wafers as shown and described.

DESCRIPTION

FIG. 1 is a front view of a container for storing and shipping wafers of the present invention;

FIG. 2 is a rear view thereof;

FIG. 3 is a top plan view thereof;

FIG. 4 is a bottom view thereof;

FIG. 5 is a right side view thereof;

FIG. 6 is a left side view thereof;

FIG. 7 is a bottom perspective view thereof;

FIG. 8 is an enlarged bottom view thereof, taken along the lines 8-8 and 8'-8' of FIG. 4;

FIG. 9 is an enlarged bottom perspective view thereof, taken along the lines 9-9 and 9'-9' of FIG. 7;

FIG. 10 is a cross-sectional view thereof, taken along the lines 10-10 of FIG. 8; and,

FIG. 11 is a cross-sectional view thereof, taken along the lines 11-11 of FIG. 8.

The Broken lines show portions of the container for storing and shipping wafers that form no part of the claimed design.

1 Claim, 11 Drawing Sheets
